UNITED STATES PATENT OFFICE

1,987,487

OIL HEATING UNIT

Richard S. Moore, Snyder, Tex.

Application September 15, 1933, Serial No. 689,646

3 Claims. (Cl. 126—93)

This invention relates to oil heating units, and has for its object the production of a simple and efficient oil heater, the parts of which may be readily and easily separated for the purpose of repair or replacement.

Another object of this invention is the production of a simple and efficient oil heater which is so constructed as to provide an efficient oil burning unit and means for passing a draft therethrough for the purpose of facilitating combustion.

A further object of this invention is the production of a simple and efficient oil heater the parts of which are simple and cheap in construction and wherein the parts may be readily assembled or detached for the purpose of permitting free access to the interior of the heater.

With these and other objects in view this invention consists in certain novel constructions, combinations and arrangements of parts as will be hereinafter more fully described and claimed.

In the drawing:

Figure 1 is a side elevation of the heater;

Figure 2 is a side elevation taken at right angles to Figure 1, the upper and lower parts being shown partly separated and certain portions being shown in section;

Figure 3 is a vertical section through the heater certain parts being broken away;

Figure 4 is a section taken on the line 4—4 of Figure 3; and

Figure 5 is a section taken on line 5—5 of Figure 3 certain parts being broken away.

By referring to the drawing, it will be seen that 1 designates the base which is provided with an 25 outwardly flared skirt 2, the skirt 2 flaring outwardly at its bottom to provide a wide and sturdy support for the heater to prevent the same from accidentally tipping over. The skirt 2 is provided with a series of perforations 3 near the bottom 40 thereof for the purpose of admitting air under the bottom plate 4 carried by the base 1. Resting upon the top edge of the base 1 is a removable top section 5 which fits over the upstanding flange 6 of the base 1, as shown clearly in Figure 3. A 45 protector ring 7 is carried near the lower edge of the top section 5 and overhangs the flange 6, as shown. The top section 5 is provided with a cover 8 having an outlet tube 9 extending through the upper central portion thereof. An inverted conical deflector or heat spreader 10 is suspended below the tube 9 in spaced relation by means of the supporting brackets 11, the deflector 10 having its outer edges 12 extending in relative close relation to the side walls of the top section 5, as shown, 55 to cause the heat to pass through a circuitous pas-

sage by hitting the deflector 10 and being spread out toward the sides and over the edges of the deflector 10, as shown by the arrows in Figure 3. The plate 4 is provided with a depending flange 4' which is bolted between the skirt 2 and the upper portion of the base 1.

Mounted within the base 1 and located above the bottom plate 4 is the fire pot 13, which fire pot is of a cup-shaped formation having a laterally extending neck 14 projecting from one side and 10 extending through the side wall of the base 1, as shown in Figure 3. This neck 14 is normally closed by a cap or lid 14'. The lid 14' may be removed for the purpose of obtaining access to the fire pot for lighting or cleaning the burner. The 15 bottom of the fire pot 13 is preferably dished toward the center and is provided with an upwardly extending neck 15 arranged centrally and constituting also a draft port, the hollow neck 15 being located directly above the aperture 16 20 formed in the bottom plate 4. A removable hollow tube 17 is fitted over the hollow neck 15 and extends upwardly to a point in close proximity to the discharge opening 18 formed in the top of the fire pot 13. Mounted within the aperture 18 or 25 discharge opening, is a removable collar 19 which constitutes an open throat for the upper end of the fire pot 13. This removable collar 19 is preferably of cast material, as is also the removable tube 17, and this collar 19 is provided with an overhanging flange 20 which overhangs the apertured supporting plate 21 which is carried near the top of the base 1, as shown. The fire pot 13 is provided with a cover plate 22 which cover plate 22 is 30 provided with a central aperture registering with the aperture 18 of the plate 21 and the plates 21 and 22 may be connected together by means of suitable rivets 23. The fire pot is provided with a series of air vent apertures 24 near the top thereof, and just above the liquid level indicated 35 by the line x—x on Figure 3. By forming the tube 17 and collar 19 of cast metal, they will serve to strengthen the neck 15 and plates 21 and 22, and prevent them from being damaged by hot gases passing upwardly from the fire about the 40 tube and through the collar. Having these elements formed separate from the neck and plates also permits easy removal and replacement of the same when it is necessary to clean the stove.

An oil reservoir or tank 25 is supported in any 50 suitable or desired manner to one side of the base 1 and is of the conventional type common to the trade whereby the liquid level is normally maintained at a specific point. Leading from the base 26 of the tank 25 is an oil supply pipe 27 which 55

extends through the base 1 and into the fire pot 13 near the bottom thereof for the purpose of supplying oil to the fire pot. A suitable brace 28 is secured to the skirt 2 and also to the pipe 5 27 near its outer end to constitute a brace therefor. A control valve 29 is carried by the outer end of the pipe 27 to manually control the flow of oil when desired. A shield plate 30 may be interposed between the tank 25 and the body of the 10 stove to shield the tank 25 from the heat of the stove.

The operation of the device is as follows:—Oil is fed through the pipe 27 into the fire pot 13 where it will seek its level, as indicated by the 15 line x—x in Figure 3. The lid 14' may be removed from the neck 14 to permit the ignition of the oil within the fire pot when desired. The burning of the oil in the fire pot 13 is facilitated by the air passing up through the apertures 3 and 20 through the apertures 24 and this will greatly facilitate the combustion of the gas by vaporizing the oil. The draft will also continue up through the neck 15, through the hollow tube 17, out through the throat plate 19, and will be deflected by the deflector 10 and finally passed out 25 through the outlet neck 9.

The fire pot 13 is preferably constructed of cast steel whereas the bottom or base 1 is preferably constructed of pressed steel. The collar 19, as 30 well as the hollow tube 17 will be preferably formed of cast metal and they are removable for the purpose of facilitating repair or replacement. It should be understood that the present heating unit may also be used with other fuel tanks located 35 remotely from the heater so long as suitable means are provided to prevent the flooding of the fire pot. It should be understood further that a very simple and efficient heater has been provided, the parts of which may be readily detached or separated for the purpose of repair or 40 replacement and that the parts are so connected as to prevent them from becoming accidentally disconnected or displaced.

Certain detail changes in the mechanical construction may be employed without departing 45 from the spirit of the invention, so long as these changes fall within the scope of the appended claims.

Having described the invention, what is claimed 50 as new is:—

1. A heater comprising a cylindrical base, a bottom plate for said base having an enlarged opening formed therein, means to support the base in an elevated position, a fire pot disposed 55 above said bottom plate within the base and having an upwardly extending hollow neck aligned with the opening of the bottom plate, walls of the fire pot being spaced from walls of the base and perforated to form draft vents, a top plate 60 for said fire pot resting thereon and formed with an opening aligned with said neck, a supporting

plate in said base resting thereon about the opening thereof and having an opening registering with the opening of the top plate, a collar extending through the openings of the supporting plate and top plate, said supporting plate diverging upwardly from the top plate and having an upstanding marginal flange contacting with the walls of the base and projecting upwardly therefrom, a top section fitting about the projecting upper portion of the flange of said supporting plate and resting upon the upper edge of said base, and a fuel pipe extending through spaced walls of the base and fire pot into the fire pot with its inner end spaced from the neck. 5 10 15

2. A heater comprising a cylindrical base, a bottom plate for said base formed with a central opening, means to support the base in an elevated position, a fire pot in said base, a clean out neck extending transversely from said fire pot through a side portion of the base, a neck rising from the bottom of said fire pot in alignment with the opening in the bottom plate, a frusto conical top for said fire pot having its marginal portions resting upon upper edges of walls of the fire pot, the walls of the fire pot being formed with draft 20 25 perforations above the liquid level of the fire pot, an inverted frusto conical supporting plate in said base having its central portion contacting with the central portion of said top, the contacting portions of the top and supporting plate being 30 35 formed with registering openings aligned with said neck, a collar fitted through the registering openings of the top and supporting plate, fasteners for holding the top and plate together extending through the top and supporting plate and 40 45 spaced radially from their contacting portions, said supporting plate having an upstanding marginal flange projecting upwardly from walls of the base, an upper stove section resting upon walls of the base about the upwardly projecting portions of the flange of the supporting plate, and a fuel pipe extending into said fire pot.

3. A heater comprising a cylindrical base, a skirt for said base formed separate therefrom, a bottom plate for said base resting upon said skirt 45 and having an enlarged opening formed therein, said bottom plate having a marginal flange surrounding the upper end of the skirt and said base having its lower portion fitting about the flange and secured by fasteners passed through the flange 50 and upper portion of the skirt, a fire pot disposed above said bottom plate within the base and having an upwardly extending hollow neck aligned with the opening of the bottom plate, walls of the fire pot being spaced from walls of the base and 55 perforated to form draft vents, and a fuel pipe extending through spaced walls of the base and fire pot into the fire pot with its inner end spaced from the neck.
